Filed Jan. 10, 1964, Ser. No. 337,039
5 Claims. (Cl. 99—171)

The present invention relates to the preservation of perishable materials containing animal or vegetable matter which is subject to spoilage caused by bacteria or molds. The invention is primarily concerned with the preservation of such materials by maintaining them in a bactericidal and fungicidal atmosphere.

Extensive work has already been done on various methods and materials to be used in preventing the spoilage of perishable organic matter. One general approach to this problem, extensively employed in the field of food preservation, has been to package the particular food commodity in an evacuated container. By the removal of air and moisture, the processes of deterioration are greatly retarded. Other methods involve heating the material to sterilizing temperatures prior to packing or storage. Another approach to the problem, sometimes used in conjunction with the vacuum packing or heat sterilizing methods previously noted, has been to flood the container with a sterilizing agent prior to closing of the package, so that a sterilizing atmosphere is maintained until the package is opened.

In processes of the latter type, considerable attention has been directed to the use of epoxides, such as ethylene oxide and propylene oxide, as sterilizing agents. Although the epoxides have been found to exhibit excellent bactericidal and fungicidal activity, certain serious disadvantages have sharply limited their usefulness.

Among the more serious drawbacks involved in the use of epoxides as sterilizing agents is the explosive character of epoxide-air mixtures. This problem presents a serious safety problem in large scale commercial packaging processes employing such materials and makes the epoxides generally unsuited to home use, i.e., use in packages which are distributed directly to the consumer and are taken into the home, as opposed to bulk commercial packaging.

Another disadvantage in the use of the epoxides has been their tendency to quickly volatilize and escape from the storage container. When sealed containers into which epoxide sterilizing agents have been introduced are opened, the epoxide vapors escape almost instantaneously. The epoxide vapors also escape very rapidly from containers which are not hermetically sealed and they may even escape rapidly from many types of sealed containers, since a number of conventional packaging materials are readily permeated by the epoxide vapors.

In order to overcome this problem, attempts have been made to utilize the epoxides in the form of solutions in solvents, such as carbon dioxide, isopropyl formate and ethylene dichloride which tend to lower the vapor pressure of the epoxides. However, such epoxide solutions have not been entirely successful due to cost, adulteration of the flavor, color or texture of foods contacted by the solutions, the production of undesirable residues and the like. In addition, the lowering of the vapor pressure in solutions of this type is only sufficient to enable the epoxide to be handled as a liquid and introduced into the package. Thereafter, the epoxide vaporizes rapidly and is subject to the same drawbacks noted in the previous paragraph.

As between ethylene oxide and propylene oxide, it has been found that the latter is generally more satisfactory

as a sterilizing agent, for a number of reasons. For example, upon reaction with water or moisture in the presence of food, propylene oxide hydrolyzes to form propylene glycol which is substantially non-toxic when consumed in amounts of the magnitude that would be found on or in food packaged in an atmosphere of propylene oxide. On the other hand, ethylene oxide hydrolyzes to produce ethylene glycol which is considerably more toxic. Also, while both propylene oxide and ethylene oxide are explosive when mixed with air, propylene oxide-air mixtures are explosive over a much narrower or more restricted composition range than are mixtures of air and ethylene oxide. Another important advantage of propylene oxide is that it is a liquid under normal conditions of temperature and pressure and therefore is easier to handle than ethylene oxide which is normally a gas.

No entirely satisfactory method for using ethylene oxide as a bactericide for organic matter is presently available. Notwithstanding the advantages of propylene oxide over ethylene oxide, no fully satisfactory method for safely and efficiently utilizing propylene oxide as a bactericide and fungicide for the preservation of food-stuffs and other animal and vegetable matter has as yet been developed. Especially lacking has been a suitable method for utilizing ethylene oxide or propylene oxide to sterilize packaged foods which are sold to the consumer and which may not be sealed against the atmosphere or may be opened and reclosed a number of times before the contents of the package are exhausted.

30 A satisfactory method for the use of ethylene oxide or propylene oxide as sterilizing agents in commercial bulk or retail scale packaging should be convenient, economical and safe. Conventional methods have required special containers or filling apparatus which are both 35 complicated to use and are expensive. Other common techniques have used the epoxides in vapor form and introduce a considerable explosion hazard.

It is, therefore, an object of the present invention to provide safe, convenient and economical methods and 40 compositions for employing ethylene oxide and/or propylene oxide as sterilizing agents for organic matter.

A further object of the invention is to provide methods and compositions for sterilizing organic matter by the use 45 of ethylene oxide and/or propylene oxide which are safe, require no special receptacles and do not call for expensive or elaborate equipment to maintain special conditions of temperature or pressure during their use.

50 A further object of the present invention is to provide a safe and efficient method for using ethylene oxide and propylene oxide as sterilizing agents without serious danger of explosion.

55 A further object of the present invention is to provide compositions comprising ethylene oxide and/or propylene oxide and methods employing such compositions which enable animal and vegetable matter to be preserved from spoilage safely and conveniently and over extended periods of time.

Another object of the invention is to provide a method 60 and compositions for preserving food by maintaining the food in an atmosphere comprising ethylene oxide and/or propylene oxide vapors.

An additional object of the present invention is to provide a method and composition for packaging food, especially food for distribution to consumers so that a sterilizing atmosphere of propylene oxide may be maintained in the package over an extended period of time.

The manner in which the foregoing objects and many other highly desirable objects are realized will be apparent in the light of the following detailed description of the invention and by reference to the accompanying drawings.

In the drawings:

FIG. 1 is a side cross-sectional view of a container including a sterilizing composition in accordance with the present invention;

FIG. 2 is a side cross-sectional view of a container comprising another composition in accordance with the present invention;

FIG. 3 is a side cross-sectional view of a portion of a sheet of packaging material coated with a sterilizing composition of the present invention;

FIG. 4 is a side cross-sectional view of a portion of a sheet of packaging material comprising a sterilizing composition of the present invention; and

FIG. 5 is a side cross-sectional view of a package made from the material of FIG. 3 or FIG. 4.

The present invention generally comprises the preservation of animal and vegetable matter from spoilage by exposing such materials to an atmosphere of ethylene oxide and/or propylene oxide vapors and by providing for the relatively slow and controlled release of the ethylene oxide and/or propylene oxide vapors into the atmosphere surrounding the material to be protected.

In accordance with the invention, compositions are provided which are capable of slowly releasing or diffusing sterilizing ethylene oxide and/or propylene oxide vapors over extended periods of time so that the sterilizing atmosphere may be maintained and continuously regenerated in circumstances where the food or other materials is temporarily exposed to the atmosphere, where the container is not air tight or where the container is constructed at least in part from materials pervious to air, moisture or propylene oxide vapors.

The invention also comprises compositions containing ethylene oxide and/or propylene oxide which are safe to use, which gradually release sterilizing vapors and which are so economical that they are entirely disposable.

According to one principal embodiment of the present invention, animal or vegetable matter which is to be preserved is placed in a container together with an amount of molecular sieve having absorbed therein ethylene oxide and/or propylene oxide as a sterilizing agent. It has been found that molecular sieves absorb moisture in preference to alkylene oxides so that as moisture is absorbed from the food or from the atmosphere surrounding the food or other organic matter in the container, alkylene oxide is gradually released from the molecular sieve into the atmosphere to maintain the contents in a sterilizing condition. The moisture, when absorbed in the sieve, results in desorption of the ethylene oxide or propylene oxide. The moisture may be taken from the contents of the container, such as a foodstuff, or from the atmosphere present when the container is closed or admitted when the container is temporarily opened. Thus, not only does the molecular sieve function as a reservoir for the epoxide sterilizing agent, but it also simultaneously provides a dehydrating function which further contributes to the inhibition of mold growth and other processes of spoilage.

The slow diffusion or exudation of ethylene oxide or propylene oxide vapors from the molecular sieves has the added very important advantage that diffusion takes place more rapidly in high moisture containing atmospheres. Since it is under conditions of high relative humidity that the danger of spoilage is most acute, the fact that the release of the sterilizing agent takes place more rapidly under such conditions is an especially important aspect of the invention. The release of absorbed sterilizing agents from other adsorbents would not ordinarily be responsive to changes in relative humidity.

Another important embodiment of the present invention comprises the introduction of ethylene oxide or propylene oxide liquid or gas into closed tubes, packets, capsules or the like which are pervious to propylene oxide vapors and the insertion of such epoxide containers into a package or receptacle containing material to be pre-

served against spoilage. This method enables the diffusion of the epoxide vapors to be controlled so that the sterilizing agent is continuously but gradually diffused through the wall of the capsule into the atmosphere surrounding the food or similar material.

A preferred method for carrying out this embodiment of the invention comprises introducing liquid ethylene oxide and/or propylene oxide into a sealed tube or capsule of a plastic which is permeable by the alkylene oxide vapors. For example, polyethylene is a very suitable material for use in forming the capsules or tube to receive the sterilizing agent.

It will be understood that other materials capable of holding liquid or vaporized ethylene oxide and/or propylene oxide and of diffusing their vapors may also be used in place of the polyethylene. In addition, the wall thickness of the particular material and the rate at which it permits propylene oxide vapors to pass may be selected so as to best suit the particular circumstances. Other film-forming materials through which ethylene and propylene oxides will diffuse and which are therefore useful in the present invention include ethyl cellulose, rubber hydrochloride, cellulose acetate, cellulose nitrate and polypropylene.

Another very important embodiment of the invention comprises the incorporation of liquid propylene oxide into a fixative which enables ethylene oxide and/or propylene oxide vapors to be slowly and gradually exuded or diffused. The preferred method for accomplishing this embodiment of the invention comprises dissolving propylene oxide in a film-forming fixative. This solution may then be used as a coating or impregnant on various materials used for the packaging of food or similar commodities. Examples of such fixatives are polyethylene glycol polymers having molecular weights ranging from about 200 to about 600 or higher, cellulose acetate, cellulose nitrate, shellac, etc.

Although the incorporation of ethylene or propylene oxide in capsules permeable to their vapors or in fixative coatings does not have the self-regulatory feature of molecular sieves containing absorbed oxides, their slow but constant release of the oxide acts effectively over a period of time and they avoid the need for using high temperatures or low pressures and are much safer to handle than prior compositions and methods.

The use of molecular sieves containing absorbed propylene oxide to sterilize foodstuffs or the like is illustrated in FIG. 1 of the drawing. As will be seen by reference to this figure, container 10 is filled with a material 11 which is to be preserved against spoilage. One or more pellets of molecular sieve 12 containing absorbed ethylene oxide or propylene oxide are introduced into the container to furnish the desired sterilizing atmosphere.

It will be understood that the contents 11 of the container 10 may be any material of animal or vegetable origin which may be attacked by bacteria or mold. Likewise, the container 10 may be of any size and construction. For example, it may be the familiar small volume metal can or jar employed in sales to the consumer and having a volume of from a few ounces up to one or two quarts. On the other hand, the container may be a drum of considerable capacity used in commercial operations and having a volume of many gallons. Similarly, the container may be constructed of metal, plastic, paper and combinations of these and other conventional packaging materials.

If desired, the molecular sieve pellets 12 may be segregated from the contents 11 of the container by a perforated diaphragm 13 which freely permits transfer of moisture and the ethylene oxide or propylene oxide vapors between the molecular sieve compartment 14 and the other compartment 15 in which material subject to spoilage is located.

Where the contents of the container to be preserved are materials for internal human or animal consumption,

propylene oxide is used as the sterilizing agent since its residue is substantially non-toxic. Otherwise, ethylene and/or propylene oxide may be used.

It will also be understood that the amount of molecular sieve and alkylene oxide composition may be varied in accordance with the size of the container and its intended or usual method of use. For example, if the container is the type which is sealed air tight and then is ordinarily opened, emptied, and disposed of, then only enough of the sterilizing composition need be included to maintain sterility within the container prior to opening. However, if the container is of a type which is ordinarily opened, partially emptied and reclosed, more of the molecular sieve-propylene oxide composition may be desirable, so that the sterilizing atmosphere may be regenerated a number of times as the container is opened and reclosed.

Molecular sieves of the type used in this invention are crystalline metal aluminosilicate materials of the following general formula:

in the salt form, where n is the valence of the metal cation M , M ordinarily is Na or K but may be other cations substituted by exchange, Y is the number of moles of alumina and Z is the number of moles of water of hydration.

Upon removal of the water of hydration by heating, the crystalline metal aluminosilicates become highly porous and are characterized by a series of surface cavities and internal pores which form an interconnecting network of passageways within the crystal. Due to the crystalline nature of such materials, the diameters of the surface cavities and of the internal pores is substantially constant and is of molecular magnitude. For this reason, the crystalline metal aluminosilicates have found wide use in the separation of materials according to molecular size or configuration, hence the name molecular sieves.

Molecular sieves or crystalline aluminosilicates are also sometimes referred to as crystalline zeolites and are of both natural and synthetic origin. Synthetic materials include, for example, synthetic faujasite. Natural crystalline aluminosilicates exhibiting molecular sieve activity include for example, analcrite, paulingite, ptilolite, clinoptilolite, ferrierite, chabazite, gmelinite, levynite, erionite and mordenite.

Since not all of the natural crystalline aluminosilicates are available in abundance, considerable attention has been directed to the production of synthetic equivalents. A number of these are available on a commercial scale and are designated as X molecular sieve, Y molecular sieve, and A molecular sieve. Other molecular sieves which have been synthesized include B, F, G, H, K-G, J, L, M, K-M, Q, R, S, T, U and Z zeolites.

While it is contemplated that any molecular sieve which absorbs water with preference to ethylene oxide or propylene oxide will be suitable for use in accordance with the present invention, it has been found that the Linde 13X molecular sieve is especially satisfactory. The synthesis and composition of the X molecular sieves are described in U.S. Patent No. 2,882,244, Milton, issued Apr. 14, 1959. Y molecular sieve is described in Belgian Patent 577,642, and A molecular sieve is described in U.S. 2,882,243, Milton and 2,982,612, Barrer et al.

The numerical prefix in the designation or identification of various molecular sieves indicates the approximate pore size in angstroms. For example, 13X molecular sieve is a sieve of the X type which is believed to have pores having diameters of about 13 angstroms. On the other hand, a 5A molecular sieve is a synthetic crystalline aluminosilicate of the A type having pores the diameters of which are approximately 5 angstroms.

In accordance with the present invention, sterilizing compositions are prepared by heating a molecular sieve material, preferably in the form of compacted pellets, spheres or the like to remove moisture and then causing

the dried sieve to be impregnated with ethylene oxide or propylene oxide. The impregnation may be accomplished by immersing crystals or pelleted crystals of the molecular sieve in liquid ethylene oxide or propylene oxide or by placing the pellets or crystals in a closed vessel containing the oxide vapors.

As an example of the later method, 123 tablets of 13X molecular sieve having a thickness of $\frac{1}{4}$ " and a diameter of $\frac{3}{4}$ " were baked overnight in an oven at a temperature of 500° F. to drive off absorbed moisture. The dried tablets were then quickly transferred to a porous bag and the bag was suspended in a closed glass container above the level of liquid propylene oxide placed in the bottom of the container. The molecular sieve was thus exposed for a period of 5 days during which time the temperature was maintained at about 45° F. Upon weighing, it was found that the molecular sieve had adsorbed about 20% by weight of propylene oxide into its pores.

As demonstrated in the following examples, the molecular sieve-propylene oxide composition is quite effective in preventing or reducing the spoilage of various food-stuffs.

Examples 1-3

Sixty-nine gram portions of pumpkin meat were placed in each of three polyethylene bags. The first bag, used as a control, was folded closed and the fold was secured with adhesive tape.

The following amounts of molecular sieve saturated with from about 20% to 40% by weight of propylene oxide were then inserted in the other two polyethylene bags, and they were closed in the same manner as Bag No. 1:

	Grams
Bag No. 2	1.6
Bag No. 3	3.2

After four days, the pumpkin meat in Bag No. 1 was observed to be covered with heavy black fungus. The pumpkin meat in Bag No. 2 showed some softening and the presence of a considerable amount of liquid, but the fungus growth was not as extensive as in Bag No. 1. The pumpkin meat in Bag No. 3 was in good condition.

Example 4

Sliced fresh tomatoes were placed in two glass jars. In one of the jars was placed one tablet of a 13X molecular sieve saturated with about 20% by weight of propylene oxide. The tablet was $\frac{3}{4}$ " in diameter and $\frac{1}{4}$ " thick. Both jars were then sealed.

Example 5

The same procedure was then followed with sliced bologna.

Example 6

The procedure was then followed with pieces of cheese cake.

After one week, observation of the food in the jars showed the following results:

	Control	Protected by Molecular Sieve Propylene Oxide
Sliced Tomatoes	Slices covered with white fungus.	No evidence of fungus.
Sliced Bologna	Slices showed spots of both white and black fungus.	Do.
Cheese Cake	Cake showed several spots of blue fungus.	Do.

It will be seen from the above examples that the incorporation of molecular sieve material saturated with propylene oxide into food packages greatly extends the period of time over which such materials may be protected from spoilage. When other forms of propylene oxide sterilizing gas are incorporated into food containers, such as liquid propylene oxide, solutions of propylene

oxide or the like, the gas volatilizes quite rapidly and is substantially lost almost immediately upon opening of the package or exposure of the propylene oxide to the atmosphere. According to the present invention, however, it is seen that the sterilizing effect achieved by the propylene oxide saturated molecular sieve persists for extended periods of time.

The manner in which food and like materials may be preserved over extended periods of time by incorporating a capsule containing propylene oxide into a container in which food or like material is placed and where the capsule is formed from material which is pervious to propylene oxide vapors is demonstrated in the following examples.

Example 7

A slice of bread and two drops of water were placed in a polyethylene bag and the bag was folded closed. A second slice of bread, two drops of water and a tube of polyethylene containing 10 cc. of propylene oxide were then placed in a second polyethylene bag which was likewise folded closed.

After twelve days, it was observed that fungus growth had begun on the slice placed in the first bag, but that no fungus growth had commenced on the slice of bread placed in the bag with the polyethylene tube containing propylene oxide. Upon observation after several months, no fungus growth was found to have commenced on the slice of bread in the bag containing the tube of propylene oxide.

Example 8

A slice of bread inoculated with a penicillin fungus was placed in a first polyethylene bag and the bag was folded closed. A second slice of bread inoculated with the same amount and type of penicillin fungus as the first slice was placed in a second polyethylene bag with a polyethylene tube containing 12 cc. of propylene oxide. The bag was then folded closed.

After five days, extensive mold was observed on the slice of bread placed in the first bag. The slice of bread placed in the second bag with the tube of propylene oxide was free from mold. Again, as in Example 7, observation after the elapse of several months showed no mold to be present on the slice of bread in the second bag.

According to the second major embodiment of the invention, as illustrated in FIG. 2 of the drawing, food 21 and a tube 22 containing ethylene oxide and/or propylene oxide 23 are placed into an outer container 24 and the container is then closed. The tube preferably is polyethylene or other plastic which is pervious to the alkylene oxide vapors and which enables the vapors to diffuse through the wall of the tube into the atmosphere surrounding the food 21.

Tube 22 may be dropped into the container with the food or may be adhesively attached to the bottom of container 24 or to its side walls or may be placed in a pocket, clamp or recess in a wall of the container or in the closure.

As one alternative to this embodiment, the plastic used to form the tube may be of a water soluble or disintegrable nature and may be edible as well, so that if the food placed in the container contains substantial amounts of water, the tube will disintegrate after release of the propylene oxide and will leave no undesirable residue.

The third major embodiment of the present invention, as previously described, generally comprises dissolving or dispersing ethylene oxide and/or propylene oxide in a fixative which gradually releases propylene oxide vapors to the atmosphere. The fixative is preferably a film-forming substance which can be used to coat or impregnate packaging materials. If at least part of an interior wall of a package made from such material carries such a coating, propylene oxide vapors will gradually be released to the atmosphere within the package.

As illustrated in FIG. 3 of the drawing, a specific example of material prepared in accordance with this in-

vention may comprise a conventional paper-foil laminate of the type widely used for packaging foods. The laminate comprises a layer of paper 31 adhesively bonded to a foil of aluminum 32 or other impermeable material. The other surface of the paper is coated with a film 33 of a fixative containing propylene oxide. The film 33 may, for example, comprise a concentrated solution of ethylene oxide and/or propylene oxide in a polyethylene glycol polymer having a molecular weight of about 200.

As a modification of this general embodiment, the film-forming fixative solution containing ethylene oxide and/or propylene oxide may be applied as an interlayer between an impermeable foil and a vapor permeable layer.

Referring to FIG. 4 of the drawing, the laminated sheet material shown in cross-section comprises a vapor permeable layer 41, such as polyethylene, cellulose acetate or the like, a vapor impermeable layer 43, such as aluminum foil or heavy waxed paper, and an interlayer 42 which is a film of fixative containing ethylene or propylene oxide.

As the sterilizing agent is gradually released from the fixative film, such as cellulose nitrate, it diffuses through the permeable layer 41.

As further illustrated in FIG. 5, materials of the type shown in FIGS. 3 and 4 may be used to form a package 51 for foods 52, such as sliced meats, cheeses, or the like by wrapping the material around the article to be packaged and crimp sealing as at 53. In each case, the material is employed so that the impermeable foil layer 32 or 43 is on the outside so that the propylene oxide vapors may diffuse and fill the inside of the package 51.

Other methods for forming and sealing packages made from materials coated or impregnated with the fixative-propylene oxide composition will be readily apparent.

It will also be seen that the relative amounts of fixative and propylene oxide or ethylene oxide in the present compositions may be varied and that the compositions may be applied to a great variety of packaging materials with the same beneficial results. For example, any rigid or flexible packaging or wrapping material, whether of paper, cardboard, wood, plastic, or metal, or of either single ply or laminated construction, may be coated over part or all of one or both surfaces so that in packages or containers formed from the material, the ethylene oxide or propylene oxide sterilizing agent in the fixative is released within the container.

While the present invention has been fully described and illustrated with reference to certain preferred embodiments, it will be apparent to those skilled in the art that various modifications may be made without departing from the spirit of the invention or the scope of the following claims.

What is claimed is:

1. A method for the preservation of perishable material which comprises placing in a container which is impermeable to air animal or vegetable matter subject to spoilage by bacteria or molds and a sterilizing composition comprising a crystalline porous metal aluminosilicate and an alkylene oxide selected from the group consisting of ethylene oxide and propylene oxide absorbed within the pores of said aluminosilicate, closing said container using an airtight sealing means and maintaining said matter in a sterilizing atmosphere of said alkylene oxide vapors for an extended period of time by the slow and controlled release of said vapors from said sterilizing composition into the atmosphere surrounding the matter to be protected in response to changes in relative humidity within said container.
2. A method in accordance with claim 1 wherein said aluminosilicate is a synthetic molecular sieve.
3. A method in accordance with claim 1 wherein said sterilizing composition is segregated from said matter subject to spoilage by a diaphragm permeable both to moisture and said alkylene oxide vapors.
4. A method in accordance with claim 1 wherein said matter subject to spoilage is intended for internal human

or animal consumption and said sterilizing composition is propylene oxide absorbed in said aluminosilicate.

5. A method for the preservation of perishable material which comprises placing in a glass container animal or vegetable foodstuffs for human consumption which are subject to spoilage by bacteria or molds and a porous crystalline aluminosilicate 13X molecular sieve having propylene oxide absorbed within its pores in an amount of about 20% by weight of said sieve, sealing said glass container using an airtight sealing means and maintaining said foodstuffs in a sterilizing atmosphere of said propylene oxide vapors for an extended period of time by the slow and controlled release of said vapors from said propylene oxide-containing molecular sieve into the atmosphere surrounding the foodstuffs to be protected in response to changes in relative humidity within said container.
